LUMINOUS SIGN

Don H. Young and George A. Houseman,
Phoenix, Ariz.

Application October 25, 1948, Serial No. 56,416

2 Claims. (Cl. 40—125)

1

The present invention relates to luminous signs and particularly to signs such as luminous street number signs such as are used for residential identification, street identification, and the like. It relates more particularly to signs which are visible at any time, day or night, and to simple, rugged construction and arrangements of the elements thereof.

In recent years there has been a growing demand, especially in connection with house numeral signs and the like for devices which may be placed at some distance from a building or other conventional support, for example, on a lawn or near a sidewalk or curb.

It is, therefore, one object of the present invention to construct a street or house number sign, or the like, which meets the above requirements and is simple and inexpensive and is highly weather resistant. While the invention is described and illustrated in the main as being applied to a lawn type residential house or street number sign, it will be understood that it is equally applicable to other types of signs.

It is another and a particular object of the invention to construct a simple, compact and attractive sign having numerals or other indicia elements so designed as to be clearly visible by contrast in daylight, by fluorescence or reflection by artificial light, and by phosphorescence (or radioactivity) in total darkness.

A further object of the invention is to assemble interchangeable numeral or other indicia elements, together with filler or spacing means when desired, into a simple rugged frame structure where they will be held firmly with substantial protection against weather and against tampering in a secure and attractive manner.

A still further object is to design the numeral or other indicia elements so that they may be produced economically, this being accomplished, for example, by forming the basic elements with surface features at different elevations to facilitate coating and other operations.

The invention will be better understood by a detailed description of a specific embodiment.

Fig. 1 is a front elevational view of a device suitable for use as a house number sign embodying the present invention, certain parts being shown only fragmentarily;

Fig. 2 is an end elevational view of the device of Fig. 1;

Fig. 3 is a transverse sectional view taken substantially along the line 3—3 of Fig. 1, showing certain inner structural details;

Fig. 4 is a fragmentary bottom view of the de-

vice of Figs. 1 to 3, taken substantially from the line 4—4 of Fig. 1;

Fig. 5 is a front elevational view of a number plate or block, or indicia member, forming a part of the invention;

Fig. 6 is a vertical sectional view of the element of Fig. 5, taken substantially along the line 6—6 of Fig. 5 and looking in the direction of the arrows;

Fig. 7 is a front elevational view of a spacer or filler element which may be used along with indicia elements of the type shown in Fig. 5 to fix their location;

Fig. 8 is a detail view of a spring element which may be used in one embodiment.

In the first embodiment shown, in the drawings the sign comprises a reasonably strong and rigid frame indicated generally by the reference character 11, Figs. 1, 2. The frame 11 consists of two identical units or half frames 15, each of which is complete in itself and may be used alone as the basis of a single faced sign. It is usually advantageous, however, to use two such members, as shown, these being secured together back to back (or corner to corner) in a manner to be set forth more fully hereinafter, so that a sign facing in two opposed or divergent directions, and having a closed structure within which various elements are enclosed, is provided. However, the invention contemplates also the use of a single

unit or half sign frame member 15, with associated indicia or number blocks, forming a complete usable unit. Each half frame unit may be provided with means for fastening it to the ground or to any support, but as shown herein, the assembled frame consisting of two half units is designed to be fitted with a plurality of stakes or pins 12 which may be driven in the ground, or set in concrete or other masonry, or fastened in wood or otherwise supported in or upon a base. These pins or stakes 12 also perform certain additional functions in securing the frame components together, in a preferred arrangement, as will be described presently. By means of the pin or stake elements 12, the sign may be either permanently or temporarily secured in place by attachment to the ground or to some other appropriate base.

Each unit or half frame 15 consists mainly of a display frame structure designed to hold and exhibit numeral plates or blocks, or similar units bearing letters of the alphabet or equivalent insignia. The face of the frame, as it best appears in Fig. 1, comprises an upper and substantially horizontal bar or border element adapted to

receive and hold or assist in holding certain interchangeable numeral plates or blocks, etc., at their upper edges. This element 17 is preferably integral and continuous with a left end member 19, as viewed in Fig. 1, a right end member 21, and a bottom member 23. As indicated in the drawing, the end members 19 and 21 may be embellished or ornamented as by being grooved or fluted, providing ornamental or reinforcing ribs 25. The bottom member 23, which, as shown, is preferably a heavier part of the frame, provides adequate strength and rigidity for the structure. This member 23 may also be embellished or ornamented, as by being grooved or fluted, as indicated at 27, 29. The type of ornamentation may be varied as desired. As shown, a small panel 31 may be left smooth, to receive the manufacturer's label, or to receive ornamentation or the like, this feature of course being optional. The frame members 15 may be recessed at each end, as indicated at 32, Fig. 2, for a similar purpose, also to reduce weight and bulk or save metal in manufacture, e. g. when made by casting or molding.

As best shown in Fig. 3, the top or upper border element 17 of the frame is preferably formed with a rearwardly extending flange element 33 which may form a top surface cover or closure for the sign when two half frame units are assembled back to back. In the arrangement shown, the resulting top surface of the assembly is substantially smooth and continuous.

The element 17 of frame unit 15 is also provided, as shown herein, with a rearwardly extending arm 35, as best shown in Fig. 3, so located as to lie immediately beneath and in alignment with a thickened lug element 37 which is also provided in each half frame unit 15. Thus the front frame member 15, as seen in Fig. 1, may have an arm 35 in juxtaposition with a lug 37 on the rear member 15, at the right end, while at the left end, the front member is provided with the lug 37 while the rear member has the arm 35. An arm at the right and a lug at the left makes it possible to form the half frame units 15 all identical, so that complementary parts, such as elements 35 and 37 come together when the two half frame units are assembled back to back. One or both of the members 35, 37 is provided with a threaded opening adapted to align with an opening in the other.

The frame units 15 may thus be secured together by means such as a pair of screws or bolts, or preferably, as shown in Fig. 3, the pins or stakes 12', may extend to the top of the frame and secure the parts just described together. It will be understood, of course, that the location of the arms 35 and lugs 37, and the number of each which are used, may be varied as desired. It is merely necessary that they be located and designed so as to be complementary and so as to come into juxtaposition as the frame units 15 are brought together. The openings 39 and 41, shown respectively in arms 35 and lugs 37, and the bolt or screw elements 43, are indicated in Fig. 1. The alternative construction, wherein the parts are secured together by the stakes 12', is shown in Fig. 3. Either construction may be used.

A comparable arrangement is provided for attaching together the lower parts of frame members 15. Each half frame 15 is provided, as shown herein, with one long arm 51 and one short arm 53. A plurality of each may be used, and preferably would be used on large units. For

units of moderate size, the construction shown is satisfactory and adequate. The long arm 51 is preferably braced and reinforced by a web or rib element 55, shown herein as of generally triangular shape. The shorter arm 53 is similarly reinforced or braced by a somewhat similar web or rib element 57. As with the arms 35 and lugs 37 at the top of the frame, the parts are complementary and are provided with openings which come into alignment when the two half frame members 15 are brought together. They may be secured by any bolt element, such as the threaded upper end of the stakes 12, as shown in Fig. 1, or they may merely receive the extended type of stake 12' as shown in Fig. 3. See also Fig. 4.

It will be noted that the frame units 15, comprising the elements 17, 19, 21 and 23 previously mentioned, provide a display panel or opening in which numeral elements or other insignia elements are received. Around the panel or opening, the framing elements 17, 19, etc., are rebated or recessed as indicated at 61, so that insignia or numeral elements may be positioned within the recessed area to be seen through the framed opening but to be retained within the frame. This construction is best shown in Fig. 3. Along at least two members, such as framing members 17 and 23, a secondary rebate 63 may be provided. These rebates receive respectively the character or insignia elements 71, to be described, and a backing element 65. As shown at the left of Fig. 3, there may be provided holding or securing means 67 and 69 along the upper and lower framing elements 17 and 23, respectively, to hold the character or numeral plates 71 and the like in place by engaging the back of the plate member 65. This member 65 may be a plate or sheet of metal or other material of appropriate strength and rigidity (e. g. glass, plastic, wood, fibreboard) and the detent means 67, 69 may either be secured to or form a deformable part of the frame 15. As shown they are simply struck up out of the material of the frame units. Two of each of the detent means 67, 69 are shown near each end in Fig. 1, but the number may be varied, depending upon the size of the numeral plates or blocks, their number, the rigidity of plate 65, and various other obvious factors.

The rebate 61, as indicated at the lower left part of Fig. 3, may be so proportioned as to make room for a friction retainer to hold the character or numeral blocks 71 against movement. With this arrangement, there is preferably employed a marcelled or serpentine retaining spring 70 of brass or bronze preferably (to resist rusting in the presence of water). Such a spring is shown in detail in Fig. 8. It may be of steel or other suitable material if rusting is immaterial, or if it is suitably coated or painted to withstand the elements. At the lower and upper right, as seen in Fig. 3, there may be provided a series of small studs 72 to hold type for holding the back elements 65 in place. Fasteners, such as those commonly sold under the name of "Timmerman" fasteners are quite suitable for the purpose.

Referring to Fig. 5 and Fig. 6, a typical indicia element, in the form of a numeral plate or block 71 is shown. It may consist of any appropriate material with the numeral or other indicia formed thereon in relief, preferably, and provided with a suitable coating material. For the purposes of this invention, it is desirable that the numerals or other characters formed on the plates or blocks 71 have the following properties: (1) They should be clearly visible by contrasting

colors in daylight. (2) They should be clearly visible in artificial light by being fluorescent or reflective, fluorescence being preferable. (3) They should be clearly visible in total darkness by phosphorescence or radioactivity.

The body material of plates or blocks 71, Fig. 6, is phosphorescent per se, being formed of a plastic material which is impregnated with a material which will cause it to glow in total darkness. Preferably, it is also impregnated with a fluorescent material, and when this is done, the characters may be formed in color or the background may be colored to contrast. In one modification commercially available synthetic resin plastics, which can be molded into the shape and form desired, and which are impregnated with phosphorescent minerals are used. Radioactive materials which glow in darkness without requiring activation by light may also be used, of course.

It will be understood that in the preferred construction, the body or background of the numeral plate or block is phosphorescent. For contrast in darkness the number or other character should not glow. For contrast in daylight the character should differ markedly in appearance, preferably in color, from the background. For contrast in artificial light, which is relatively weak as compared with sunlight but is often too bright to permit seeing the much weaker phosphorescent light, either the numeral or the background should be fluorescent and the adjoining area nonfluorescent. According to the present invention all these requirements are met either by impregnating the body of the plate or block with both a phosphorescent or fluorescent material forming the character itself (or the contrasting background) with a paint which makes both phosphorescent and fluorescent, or by coating the numeral (or other indicia) itself with a paint or coating composition which is in strong color contrast to the background in daylight and which is impregnated with at least a moderately fluorescent material and preferably with a highly fluorescent material which masks the phosphorescent base. A sheet material which is highly fluorescent and/or reflective, may be used in lieu of paint, if desired.

To facilitate formation of the coated numeral or the like indicia, in either of the methods just described, the character itself is preferably formed with a surface raised at least slightly above the general background surface of the element 71. The difference in elevation, indicated at 75, Fig. 6, may be obtained either by casting the plastic member 71 or by milling or cutting, or abrading, etc., to leave the character raised somewhat. In one practical embodiment the elevation was of the order of .030 inch, more or less. The plates or blocks 71 are preferably provided with peripheral reinforcing flanges 73 on their rear faces, especially if they are thin enough to have appreciable flexibility.

The coating composition of layer 77 is preferably one which attaches very firmly to the material of the background element 71.

In Fig. 7 there is shown a spacer or filler ele-

ment 91 which preferably is of the same size as the character element 71. This element 91 may be used to fill up space not used by indicia elements. Element 91 is preferably provided with at least a marginal reinforcing flange 93 and preferably also is designed to be broken rather readily along a vertical line into two parts each half the size of a character element 71. Thus the spacer or filler 91 may be weakened along the central vertical division line and flanges for reinforcing purposes may be provided on either side of said line. The division line is indicated at 95 and the flanges at 97. Either half 99 of the divided filler element 91 may then be used, either between numeral elements, when spacing is desirable, or at the ends of a group of numeral elements when such a group is insufficient to fill the frame member 15. In the embodiment shown, the frame is designed to receive five elements 71. This is about the maximum ordinarily required for house numbering in cities, but of course, the number may be greater or less as desired. If, in the structure shown, the user requires only three digits for his number, he may use the three numeral blocks 71 and two spacer or filler elements 91. For symmetry one unit 91 may be used at each end with three numeral blocks 71 centrally located in the frame. If the house number requires four digits, one spacer 91 will be used, preferably being broken into two halves of which one is used at each end to center the four digits in the frame.

What is claimed is:

1. A sign comprising in combination a pair of opposed frame members adapted when assembled together to form a substantially enclosed unitary hollow structure for exhibiting sign elements on two generally opposing faces thereof, said members each including a pair of dissimilar upper and lower connecting lugs so arranged that a short lug on each member connects with a long lug on the other and vice versa, and a stake member adapted to be driven into a supporting base and projecting through a lower and upper set of said lugs to hold the opposed frame members together.

2. A sign according to claim 1 wherein each frame member is fitted with a plurality of self-luminous individual sign characters.

DON H. YOUNG.
GEORGE A. HOUSEMAN.
